FUEL DISTRIBUTOR

Frank C. Pickard, Erie, Pa., assignor to The Standard Stoker Company, Incorporated, a corporation of Delaware

Application September 18, 1930
Serial No. 482,714

7 Claims. (Cl. 110—104)

My invention relates particularly to scatter feed types of stokers in which fuel is distributed over the fire by a distributing system utilizing the propelling force of a pressure fluid blast.

5 The fuel such as coal, utilized in stokers of the character described varies in size from very fine particles to lumps of considerable size and when coal of this nature is delivered into the zone of action of an ordinary type of single pressure fluid blast, both the coarse and fine fuel are subjected to blast of the same intensity, with the result that the fine particles are driven farther into the firebox than the coarser lumps and the fuel bed is largely composed of coarse coal at the 10 back and fine coal at the front, the intervening part being graduated from coarse to fine. Attempts have been made to effect a separation of the coarse from the fine coal and subjecting the coarse coal to a high pressure fluid blast and the 15 fine coal to a low pressure fluid blast in order to project an equal amount of the fines over the entire surface of the firebox and to project an equal amount of the larger sizes all over the firebox but some indiscriminate commingling of the 20 fine coal and coarse coal takes place on the single firing table and causes the fine and coarse coal to be subjected to a blast of the same intensity.

It is the principal object of my invention to provide an improved distributing system whereby the 25 coarse fuel is equally distributed over the entire firebox and the fine fuel is also equally distributed over the entire firebox.

More particularly it is an object of my invention to provide in a pressure fluid blast distributing system an upper and a lower table, means for classifying the fuel according to size whereby the coarse fuel is collected on the upper plate and the fine fuel is collected on the lower plate, a pressure fluid blast of high intensity for projecting the 30 coarse fuel into the firebox, and a pressure fluid blast of low intensity for projecting the fine fuel into the firebox.

It is a further object of the invention to design the upper plate in such a manner that a portion 35 of the coarse fuel is delivered from the upper to the lower plate at designated places whereby the coarse fuel is subjected to the action of the low pressure blast and delivered to the rear corners of the firebox.

With these and other objects in view which will 40 be apparent as the nature of the invention is better understood, the same consists in the novel construction, combination and arrangement of parts hereinafter more fully described, illustrated and claimed.

A preferred and practical embodiment of the invention is illustrated in the accompanying drawings, in which

Fig. 1 is a vertical section of a portion of a furnace and a stoker therefor, showing the invention in position therein;

Fig. 2 is a detail plan section on the line 2—2 of Fig. 1;

Fig. 3 is a detail vertical section on the line 3—3 of Fig. 1; and

Fig. 4 is an isometric view of the distributor table arrangement.

The invention is particularly applicable to stokers for use with locomotives and for the purpose of best illustrating the invention it will 50 be so described, but its use is not so limited in its application and may equally find use with stokers for furnaces of other types where the advantages of my construction are desired.

The numeral 10 denotes a locomotive boiler 55 firebox, 11 the firing opening in the backwall 12 and 13 the grates. A suitable stoker, indicated as a whole at 14, is provided for conveying the fuel from a source of supply and delivering it to the firing opening 11. The part of the stoking 60 mechanism illustrated comprises a riser conduit 15 rigidly supported from the backwall 12 by suitable means, as by the bracket 16, and a conduit 17 leading from a source of fuel supply and universally connected at its forward end with 65 the lower end of the riser conduit 15. The riser conduit 15 is provided with a removable cover section 18 which may be hinged at its upper end and held in closed position by a latch 19, where- 70 by access may be had to the interior of the riser 75 conduit.

The fuel delivered to the riser conduit 15 is received by a novel and practical distributing system, indicated generally by the numeral 20. This means provides an arrangement whereby 80 the fine fuel and the coarse fuel is separated, collected on independent firing tables and projected into the firebox by separate fluid pressure blasts, as will now be described.

The distributing system comprises a distributor member denoted generally by the numeral 21 having an upper firing table 22 and a lower firing table 23. The upper firing table 22 constitutes a continuation of the bottom wall or floor 85 24 of the riser conduit 15, and is provided with a rectangular opening 25 in its rearward portion, a V-shaped abutment 26 at its forward portion intermediate of the sides of the table, the indentations 27, 27a in the forward side portions of the table 22 and the abutment members 28, 28a. 90 95 100 105 110

The V-shaped abutment 26 serves to deflect a portion of the fuel towards the sides of the firebox and the remainder passes over the abutment supplying fuel to that portion of the firebox intermediate the sides. The indentations 27, 27a permit a portion of the fuel collected on the upper table to be dropped onto the lower firing table where it is projected into the firebox by the lower pressure blast as will be hereinafter described. The forward side portions of the lower firing table are provided with the pockets 29, 29a, and the abutment members 30, 30a which serve to receive and direct a portion of the fuel to the rear corners of the firebox.

Rearwardly of the distributor member 21 and outside of the firebox is a vertically disposed distributor head 31 to which pressure fluid such as steam is supplied by suitable supply pipes. This distributor head is provided with jet openings 32 in its forward face in a position between the lower and upper distributor plates and at the rear of the lower plate and also rearward of the riddle means of the upper plate. These openings lead from the low pressure chamber 33 of the head 31 as best seen in Fig. 3. Pressure fluid is supplied by the supply pipe 34 to the chamber 33. The distributor head 31 is also provided with forwardly extending and somewhat laterally flaring fingers or jet members 35 extending from the top of the head forward across the aperture 25 in the upper firing table or plate 22 forming therewith a riddling means 36. The fingers or jet members terminate just forward of the aperture 25 and each finger is provided with an orifice or jet opening 37 leading into either one or the other of a pair of high pressure chambers 38 and 39 within the head 31, these high pressure chambers being separated from the low pressure chamber by suitable partition walls and steam or other pressure fluid is supplied thereto by the pipes 40 and 41 respectively. Suitable valves, not shown, in each supply permit control of the pressure of fluid in each chamber. Preferably the pipe 34 supplies low pressure fluid to the chamber 33 for emitting a low pressure blast through the jet openings 32 across the lower firing table and the pipes 40 and 41 supply high pressure fluid to the chambers 38 and 39, whereby a blast of comparatively high pressure issues from the jet members 35 sweeping across the front portion of the upper firing table.

In operation the fuel advanced through the riser conduit 15, is deposited on the riddle means 36 and is urged thereover by reason of the pressure of the advancing column of fuel. As the fuel passes across the riddle the finer particles of fuel are separated from the coarse fuel and fall through the aperture onto the lower firing table 23 within the zone of action of a low pressure fluid blast issuing from the jet openings 32. This blast functions in cooperation with the lower firing table and the pockets 29, 29a and the abutment members 30, 30a thereon to distribute the fine fuel over the entire firebox. The coarse fuel tumbles over the forward end of the fingers 35 onto the upper firing plate from where it is distributed over the entire firebox by the cooperation of the high pressure blast issuing from the jet openings 37 with the upper firing table and its V-shaped abutment 26 and abutment members 28, 28a. The indentations 27 and 27a allow some of the lump fuel to fall into the rear portion of the firebox to aid in placing the lump fuel on all parts of the fire. The upper firing table 22 extends forwardly beyond the

lower firing table 23 and serves as a cover over the fine fuel being distributed by the lower table and low pressure blast.

In my construction a separation of the coarse and fine fuel occurs prior to subjecting the fuel to the action of the pressure blast, hence an almost complete separation is attained. The two divisions of fuel may then be projected by their respective jets, the larger sizes with the high pressure jet over the top firing table, and the fines over the lower firing table, with the low pressure jet. By this arrangement the fines are distributed over the fire at a point beneath the high pressure blast, which then becomes a protective covering preventing loss of the finer particles of fuel. It will be observed that the arrangement and structure of the plates and respective blasts provide an equal classification of the coarse and fine particles of fuel to all parts of the fire.

It will be apparent that the invention is capable of certain modifications without departing from the intended scope of the invention.

I claim:

1. In a fuel distributing system for scattering fuel in aerial paths over a fire, the combination of a lower firing plate having pressure fluid blast means at the rear thereof, an upper firing plate spaced above said lower plate, means for delivering fuel to said upper plate, an opening in the rearward portion of said upper plate, a plurality of fingers extending longitudinally forward over said opening forming therewith a riddle and jet openings in said fingers arranged to issue a blast of pressure fluid forward of said riddle across said upper firing plate.

2. In a fuel distributing system for scattering fuel in aerial paths over a fire, an upper and a lower firing plate each of which is arranged for the passage of fuel thereover, means for delivering fuel to said upper plate, riddling means at the rearward portion of said upper plate whereby fine fuel drops through said riddling means onto the lower firing table and the coarse fuel passes over said upper firing table, a low pressure blast means arranged to project the fines from said lower plate and blast means of higher pressure arranged to project the coarse fuel across said upper plate, and indentations in said upper plate forward of said riddling means arranged to permit a portion of the coarse fuel to drop onto predetermined parts of said lower plate, whereby such portion of coarse fuel is projected over predetermined parts of the fire by said low pressure blast means.

3. In a fuel distributing system for scattering fuel in aerial paths over a fire, an upper and a lower firing plate each of which is arranged for the passage of fuel thereover, means for delivering fuel to said upper plate, riddling means at the rearward portion of said upper plate whereby fine fuel drops through said riddling means onto the lower firing table and the coarse fuel passes over said upper firing table, low pressure blast means arranged to project the fines from said lower plate and blast means of higher pressure forward of said riddling means for projecting coarse fuel across said upper plate, and indentations in the side portions of said upper plate forward of said riddling means arranged to permit a portion of the coarse fuel to be dropped onto the forward side portions of said lower plate into the zone of action of said low pressure blast means, whereby such portion of the coarse fuel is projected over the rear corners of the fire.

4. In a fuel distributing system for scattering fuel in aerial paths over a fire, the combination of a lower firing plate having pressure fluid blast means at the rear thereof, an upper firing plate spaced over and above said lower plate and extending forwardly at least as far as the forward marginal edge of said lower plate, means for delivering fuel to said upper plate, riddling means at the rearward portion of said upper plate whereby fine fuel drops through said riddle onto the lower firing table and the coarse fuel passes over said upper firing table, and pressure fluid blast means on said upper plate acting on the fuel forward of said riddling means.
5. In a fuel distributing system, the combination of a lower firing plate, an upper firing plate spaced over and above said lower plate, an opening in the rearward central portion of said upper plate, a distributor head at the rear of said plates and a plurality of finger-like extensions formed with said distributor head and extending forwardly therefrom over the opening in said upper
6. As a new article of manufacture a distributor member in the form of a unitary structure comprising a pair of plates spaced one above the other, the upper of said plates having an opening in its rearward central portion and indentations in its forward side portions, and the lower of said plates having pockets formed in its forward side portions.
7. As a new article of manufacture a distributor member comprising a pair of plates spaced one above the other, the upper of said plates having an opening in its rearward central portion, indentations in its forward side portions, abutments bounding the forward marginal edges of said indentations, and a V-shaped abutment on the forward portion of said upper plate intermediate the sides thereof, the lower of said plates having pockets formed in its forward side portions and abutments bounding the forward marginal edge of said pockets.
